UNITED STATES PATENT OFFICE.

MICHAEL SMITH, OF PASSAIC, NEW JERSEY, ASSIGNOR TO THE RAPID ELECTRO-TYPE COMPANY, OF CINCINNATI, OHIO, A CORPORATION OF OHIO.

PRODUCTION OF MATRICES OR MOLDS FOR PRINTING-PLATES.

1,093,015.

Specification of Letters Patent. Patented Apr. 14, 1914.

Application filed February 20, 1913. Serial No. 749,641.

To all whom it may concern:

Be it known that I, MICHAEL SMITH, a citizen of the United States, residing in the city and county of Passaic and State of New Jersey, have invented Improvements in the Production of Matrices or Molds for Printing-Plates; and in order that others skilled in the art may understand, make, and use my invention I give the following description.

My invention relates to the production of printing plates, stereotypes and the like and has for its object the production of matrices or molds in which such printing plates, stereotypes and the like may be rapidly and inexpensively produced and which will produce stereotypes or printing plates of great perfection of the design or type characters and of great accuracy as to dimensions.

I have illustrated my invention and the mode of carrying out the same in the accompanying drawings, in which,

Figure 1 is a plan view of a frame for holding the set-up type or other matter from which a matrix is to be made; Fig. 2 is a cross sectional view taken on the line X—X, Fig. 1; Fig. 3 is a plan view of a frame or mold for production of a printing plate or stereotype; Fig. 4 is a cross sectional view taken on the line Y—Y, Fig. 3; Fig. 5 is a broken view illustrating a matrix, and Fig. 6 is a similar view showing a printing plate.

Similar reference numerals are applied to corresponding parts in the several views.

In carrying out my invention I take a form of set-up types, or a block or plate of typographic matter, or an engraved metal or half-tone plate bearing a design on its face and secure the same within a frame 1, as shown in Fig. 1. Such frame may be an ordinary printer's chase. For convenience of illustration I have shown a form 2 of set-up type matter secured in said frame 1, but it will be understood that where the design to be reproduced is on a relatively thin body such as an engraved metal or half-tone plate, such plate will be suitably backed up in order to bring its face to right height with respect to the frame 1, for forming the matrix thereon.

As great accuracy of size is requisite in stereotypes and printing plates in order that

they will fit into place when setting up the press, I provide for obtaining this accuracy in the size of the matrix by securing metal strips 3 around the sides of the form 2 when inserted in the frame 1. These metal strips 3 should be secured firmly and close up against the sides of the form 2 so as to accurately define the same. These metal strips 3, as shown in Fig. 2, should be so secured about the sides of the form that their upper edges come even or flush with the type faces or face of the design. The upper edges of said strips 3 are beveled outwardly, as shown at 4, so as to form sharp marking or cutting edges of the matrix, which edges coincide with the sides of the form 2 and thus accurately determine the size of the matrix, as will hereinafter more fully appear. The strips 3 may be secured in place by the screws 5, or other clamping means, by which the form 2 is locked in the frame 1; or said strips may be secured directly to the sides of the form by any suitable fastening means.

For forming the body of the matrix I employ a sheet of fibrous compressible material in which the fibers are more or less loosely felted together and saturate said material thoroughly with a solution of a gum or resin, such, for example, as shellac, gum copal or resin dissolved in wood alcohol or other solvent. For the fibrous compressible material I have found the material known as straw board, and largely used for making paper boxes, when saturated and impregnated with the gum or resin, possesses the property of taking and retaining perfect impressions of typographic and similar designs used in printing. For finer or more delicate and detailed designs I prefer to face one side of said fibrous compressible material by affixing thereto a sheet of blotting paper of about one thirty-second of an inch in thickness, said blotting paper sheet being also saturated with the gum solution. Or the matrix material may be wholly of the blotting paper of a thickness of about one-eighth of an inch, though this will increase the cost nearly three times. When the blotting paper facing is used, as above described, the straw-board sheet to which it is affixed will be about three-six-

teenths of an inch in thickness. Sheets of the character described having been thoroughly saturated and impregnated with gun- or resin solution are exposed to drying 5 to evaporate the solvent. This treatment makes the sheets quite hard and stiff; but when said sheets are brought under the influence of heat up to about 250° F. they become quite soft and pliable, resuming 10 their hardness and rigidity on cooling.

To form a matrix, a sheet or portion of the described material, about one-half of an inch larger all around than the form or plate 2 to be reproduced, is taken and heated 15 thoroughly until it is quite soft and pliable. The form or plate 2 with the strips 3 having been previously locked up in the frame or chase 1 is thinly and uniformly coated with a film of glycerin, care being taken to 20 have such coating uniform and thin, so as not to mask any of the fine lines or details of the design. The heated and soft and pliable sheet is then laid on the form or plate so prepared and firmly and evenly pressed 25 thereon, with a pressure of about fifty pounds to the square inch; though a heavier pressure may be employed if desired. Such pressure may be performed in any good and accurate press. The operation of taking the 30 impression should be performed quickly, and all the appliances required therefor should be ready, as the heated, plastic sheet cools quickly, and if permitted to cool appreciably it correspondingly hardens and 35 the impressions taken may then lack depth and sharpness. By proceeding as described the soft and pliable sheet is forced into the finest details of the design and a matrix is produced which is a perfect reproduction 40 of the design, with all the details clear and sharp, and of a depth up to the shoulders of the type with a deeper surplus for the empty spaces. When cool and hard the matrix is separated from the form or plate, 45 the previously applied film of glycerin insuring clean separation. When separated from the form or plate it will be found that the sharp edges of the strips 3 as well as the design are sharply impressed in the 50 matrix. The surplus matrix material outside the impression of the strips 3 is cut away accurately on the lines of the impression of said strips and the matrix is thus obtained of exact and accurate size. Such 55 matrix is represented in Fig. 5, in which 6 represents the body portion of straw-board or similar fibrous compressible material and 7 the facing of blotting paper.

From a matrix produced as described a 60 number of positive printing plates may be produced, particularly if made of the material hereinafter specified. For forming a printing plate or stereotype from said matrix the latter, accurately sized as described,

is suitably blocked up by placing the same 65 upon a block 8, Fig. 3, with the design face presented upwardly. Around the block 8 and close up against the edges of the same and of the matrix are secured brass strips 9. These strips 9 are beveled at their upper 70 edges as at 10, to form sharp edges, the bevel being inclined outwardly, as shown. The height of the strips 9 determines the thickness of the stereotype or printing plate to be formed. For example, if such plate is to 75 be three-sixteenths of an inch thick said strips must extend three-sixteenths of an inch higher than the face impression of the type in the matrix. If stereotypes or plates of greater thickness are desired said strips 80 will be correspondingly higher. The backed up matrix with the strips 9 closely and firmly secured about the edges of the same is locked up in a frame or chase 1, by means of the screws 5 or other locking means; 85 said screws or locking means may also serve as the means for holding strips 9 closely and securely about the edges of the matrix and block. When so arranged the matrix and strips 9 form a mold in which the material 90 for forming the stereotype or printing plate may be pressed.

Any suitable stereotype material may be employed, but I prefer to employ one that is hard or semi-hard at normal temperatures 95 and is rendered soft and plastic by heat at a temperature less than that which softens the matrix material. For such material I preferably employ that described in the application of Eugene C. Smith, Serial No. 100 746242 filed February 4th, 1913. This material can be obtained in sheets of even, straight and smooth surface and uniform in thickness throughout. As stereotypes and printing plates should be of uniform thickness for good printing, this is a feature of 105 advantage. Said material while hard or semi-hard at normal temperatures becomes soft and plastic at about 200° F. in which condition it takes perfect impressions such 110 as are required in printing plates, and does not contract on cooling. As such sheets would in their heated and soft condition be difficult to handle and apply to the matrix, I first unite such sheets to a backing of stiff 115 paper, or of wood, by means of a cement, such as shellac or celluloid cement or thin glue. Large sheets of the material, backed as described, may be prepared (say 24x30 inches in size) and kept on hand and pieces 120 of the sizes required for printing plates may be cut therefrom from time to time as needed. As great accuracy and uniformity of thickness of stereotypes and printing plates is required, the thickness of the material on 125 the backing should be greater than that required for the finished plate, to allow for the pressure exerted thereon in making the

impression. A piece of said backed material of a size somewhat larger than that required for the plate or stereotype is taken and coated with a film of the finest plumbago by means of a brush or pad, and a film of the same material is also applied to the matrix, care being taken that all loose plumbago particles are removed—the object being to give the surfaces a fine glossy impalpable coating of plumbago to insure clean separation of the surfaces after impression.

The matrix having been prepared as described and locked in frame 1, the backed sheet is placed on steam table or otherwise uniformly heated to a temperature of about 200° F. or until it is converted into a soft and plastic condition. In this condition it is laid on the matrix in said frame and the whole placed in a strong and accurately operating press and subjected to the required pressure to force said material into the design on the matrix. The pressure will force out around the edges formed by the strips 9 the surplus material, the escape of which will cease as soon as the backing comes into hard contact with the edges of the strips 9. The pressure is maintained until the material has cooled when it is removed from the press and lifted from the matrix. After trimming off the backing the stereotype or plate is ready for use. Fig. 6 illustrates such plate in which 12 is the material in which the design is impressed and 11 is the backing. The stereotype or plate so produced is accurate as to form, dimensions and thickness, is flat and smooth on the back and has its edges formed with an angle or bevel corresponding to the bevel of the strips 9, which bevel is required when the plates 40 are to be used on the so-called ready blocks to engage with the movable lock-up strips or holding clips.

It will be understood that the material referred to for forming the stereotype or printing plate is of such character that the stereotypes or plates formed thereof may be flat for use on flat bed presses; or it may be curved at any time for use on cylinder or rotary presses.

From the foregoing it will be seen that my invention provides means by which matrices may be formed readily and inexpensively; that said matrices reproduce with sharpness, depth and great perfection the design in all its fine details, and may be repeatedly used to form stereotypes and printing plates, and that the plates or stereotypes produced therefrom are accurate as to size, back and thickness and ready for use on the press without further operations.

What I claim is:

1. A matrix material for forming stereotypes and printing plates, said material consisting of a fibrous compressible material,

impregnated with a gum or resin, said material being hard and rigid at normal temperatures and soft and plastic and capable of taking fine designs by impression when heated to a temperature of about 250° F.

2. A matrix material for forming stereotypes and printing plates, said material consisting of strawboard impregnated with a gum or resin, said material being hard and rigid at normal temperatures and soft and plastic and capable of taking fine designs by impression when heated to a temperature of about 250° F.

3. A matrix material for forming stereotypes and printing plates, said material consisting of a body portion of fibrous compressible material, a facing of blotting paper on said material, said facing and body portion impregnated with a gum or resin, said matrix material being hard and rigid at normal temperatures and soft and plastic and capable of taking fine designs by impression when heated to a temperature of about 250° F.

4. A matrix material for forming stereotypes and printing plates, said material consisting of a body portion of strawboard, a facing of blotting paper on said strawboard, said body portion and facing impregnated with a gum or resin, said matrix material being hard and rigid at normal temperatures and soft and plastic and capable of taking fine designs by impression when heated to a temperature of about 250° F.

5. The process of forming matrices for stereotypes and printing plates which consists in saturating a fibrous compressible material with a solution of a gum or resin in a volatile solvent, evaporating said solvent, heating the material so treated to make the same plastic, pressing the same on the form or design to be reproduced, and maintaining said pressure until the material is cool, then separating the material from the form or design.

6. The process of forming matrices for stereotypes and printing plates which consists in saturating a fibrous compressible material with a solution of a gum or resin in a volatile solvent, similarly saturating a facing sheet of blotting paper, superposing said facing sheet on the fibrous compressible material drying said sheets to evaporate the solvent, heating said sheets to render the same soft and plastic, pressing the same on the form or design to be reproduced with the facing in contact with said design, maintaining said pressure until the material is cool and separating the material from the design.

7. The process of forming matrices for stereotypes and printing plates which consists in saturating a fibrous compressible material with a solution of a gum or resin

in a volatile solvent, evaporating said solvent, coating the form or design to be reproduced with a film of glycerin, heating the material so treated to make the same plastic, pressing the same on the form or design to be reproduced, and maintaining said pressure until the material is cool, then

separating the material from the form or design.

MICHAEL SMITH.
